UNITED STATES PATENT OFFICE.

FLORA WELSH, OF WATERVILLE, OHIO.

BED-PAN.

1,251,311.

Specification of Letters Patent. Patented Dec. 25, 1917.

Application filed January 17, 1917. Serial No. 142,846.

To all whom it may concern:

Be it known that I, FLORA WELSH, a citizen of the United States, residing at Waterville, in the county of Lucas and State of Ohio, have invented certain new and useful Improvements in Bed-Pans; and I do hereby declare the following to be a full, clear, and exact description of the invention, such as will enable others skilled in the art to which it appertains to make and use the same.

This invention relates to new and useful improvements in a bed pan and has for one of its objects the provision of a device of this character, which shall be simple, durable and efficient, and which may be manufactured and sold at a comparatively low cost.

Another object of this invention is to provide a body portion having an inclined top removably secured thereon and provided with a pear shaped opening providing a very efficient and comfortable seat for a person while in use and which will prevent any of the contents from spilling therefrom when the device is accidentally tipped or tilted while in use.

A further object of this invention is to provide a top having a handle and of such shape as to fit the opening in the top, so that the device may be readily closed after being used to render a sanitary device.

With these and other objects in view as will become more apparent as the description proceeds, the invention consists of certain novel features of construction, combination and arrangement of parts as will be hereinafter more fully described and claimed.

For a complete understanding of my invention, reference is to be had to the following description and accompanying drawing, in which:

Fig. 1 is a plan view of a bed pan constructed in accordance with my invention,

Fig. 2 is a longitudinal sectional view of the same,

Fig. 3 is a transverse sectional view of the same,

Fig. 4 is a plan view of the top.

Referring in detail to the drawing, the 50 numeral 1 indicates as an entirety, the body of my improved bed pan consisting of a bottom 2 having upstanding walls 3 formed thereon. A top 4 has a downwardly depending flange 5 formed thereon which is received by the upstanding walls 3. The top 4 is provided with a substantially pear shaped opening 6, the smaller end of which opens outwardly. The edge of the top 4 that forms the pear shaped opening 6 is 60 bent downwardly to form a flange 7, which provides a smooth and comfortable seat to the user. The top 4 is provided with an upwardly inclined portion 7' at its rear end while its sides incline downwardly to 65 form an inclined seat or rest for the user.

A substantially pear shaped cover 8 has downwardly depending flanges 9 formed thereon adapted to be received within the substantially pear shaped opening 6 of the 70 top 4, whereby the device may be entirely inclosed forming a sanitary bed pan. Upstanding arms 10 are secured to the cover 8 in spaced relation and are connected together by a suitable hand grip or handle 75 11, whereby the cover 8 may be readily removed and replaced upon the top 4 when desired.

From the foregoing description taken in connection with the accompanying drawing, 80 it will be noted that a sanitary bed pan has been provided, which can be readily assembled for cleansing purposes, and each part being so constructed that all foreign matter 85 can be readily cleaned therefrom when desired.

While I have shown and described the preferred embodiment of my invention, it will be understood that minor changes in construction, combination and arrangement 90 of parts may be made without departing from the spirit and scope of the invention as claimed.

What is claimed is:

A bed pan comprising a bottom, upstanding flanges formed on said bottom, a top, downwardly extending flanges formed on 95 said top and received by the first named

flanges to support the top, said top being inclined downwardly and having a pear shaped opening therein, said opening extending through one edge of the top and being closed by the first named flanges, and a pear shaped cover closing said opening.

In testimony whereof I affix my signature in presence of two witnesses.

FLORA WELSH.
